WINDOW VENTILATOR

James A. Webb, New York, N. Y.

Application June 18, 1936, Serial No. 85,930

7 Claims. (Cl. 98—100)

This invention relates to air-conditioning devices. It is particularly directed to a window ventilator, and the like articles.

An object of this invention is to provide a window ventilator of the character described, having means to eliminate dust from air entering the room, while yet permitting a free flow of air therethrough.

A further object of this invention is to provide a ventilator of the character described, which may be readily mounted in position on a window frame and in which water is employed to remove dust from the air entering the room and to add moisture to the air for conditioning the same.

Still another object of this invention is to provide a neat, compact and durable window ventilator of the character described, which shall be relatively inexpensive to manufacture, easy to install and clean, and withal, practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is an outside elevational view of a window frame provided with an air-conditioning window ventilator embodying the invention;

Fig. 2 is a cross-sectional view taken on line 2—2 of Fig. 1;

Fig. 3 is a partial elevational inside view of the ventilator with parts broken away to show the interior construction; and

Fig. 4 is an elevational cross-sectional view of a portion of the window frame and windows slidably mounted therein, and illustrating a device forming part of my invention for preventing air from flowing between the windows.

Referring now in detail to the drawing, 10 designates a window frame of usual construction and 11 designates a window slidably therein. The frame 10 comprises a bottom portion 13 and side portions 14. Mounted within the frame 10 and below the window 11 is an air-conditioning window ventilator 15 embodying the invention.

The ventilator 15 may be made of wood, galvanized iron or other suitable sheet metal. The same comprises a case 16 and a removable cover 17 for said case. The case 16 has a flat bottom wall 19 adapted to rest on the bottom of the frame 13. Extending upwardly from the front of the bottom wall 19 is a vertical front wall 20; and extending upwardly from the rear of said

bottom wall is a rear vertical wall 21. The rear wall 21 extends to a higher level than the wall 20 and terminates in a top edge 21a. Extending rearwardly from the top of the front wall 20 is a top wall 22, terminating short of the wall 21 and provided with a downwardly extending flange 23. The front wall 20 has, adjacent the top thereof, a plurality of spaced openings or perforations 25 for the purposes hereinafter appearing. The rear wall 21 has, adjacent the top thereof, a plurality of spaced openings or perforations 26, the purpose of which will be explained hereinafter. Said front wall is also provided at a bottom corner thereof with a removable screw plug 27 for draining water within the case 16, as will appear hereinafter.

The case 16 further comprises end walls 29 to close the ends of the case. The end walls 29 interconnect the top wall 22 with the bottom wall 19 and each has a front vertical edge 30 extending above the top wall 22 and a top horizontal edge 31 somewhat below the level of the top edge 21a.

The cover 17 has a top wall 35 contacting the edges 31 of the end walls 29 and a folded-over channel 36 adapted to frictionally engage the upper edge 21a of the rear wall 21. Extending downwardly from the wall 35 is a vertical wall 38 contacting the edges 30 and projecting into the case 16. The lower end of the wall 38 projects below the flange 23 and serves as a baffle for air entering the openings 26 and passing through the case to the openings 25. The portion of the wall 38 which extends below the top wall 22 of the case 16, is preferably somewhat narrowed to permit insertion thereof into the case.

As shown in Fig. 2 of the drawing, the bottom of the window 14 contacts the wall 35 of the cover 17, so that air entering the room must pass through the ventilator. Water may be placed into the case 16, the level of the water being below the bottom edge of the wall 38 of the cover 17.

It will now be understood that air entering the room must first pass through the openings 25 beneath the baffle 38 and through the openings 26 as indicated by the arrows in Fig. 2 of the drawing. The air while passing through the ventilator is cooled and cleaned of dust by the water and gathers moisture to condition the air. The water may be removed from the ventilator by unscrewing the plug 27.

It will be noted that the front window 11 is moved down into contact with the top of the ventilator 15 as shown in Fig. 2 of the drawing. Means is also provided to prevent air from flowing between the front and rear windows and thus entering the room, whereby air can only enter the room through the ventilator. When the front window is in contact with the top of the venti-

lator 15, the rear window 11a is raised. The bottom portion 11b of the window 11a is below the top portion of the front window 11. As shown in Fig. 4 of the drawing, there is attached to the bottom of the window 11b, a rubber strip 40, the front edge of which contacts the pane 11c of the window 11, and hence prevents air from passing between the windows. Any air entering the room through the frame 10 must therefore pass through 10 the ventilator 15.

It will thus be seen that there is provided a device in which the several objects of this invention are achieved, and which is well adapted to meet the conditions of practical use.

15 As various possible embodiments might be made of the above invention, and as various changes might be made in the embodiment above set forth, it is to be understood that all matter herein set forth or shown in the accompanying drawing 20 is to be interpreted as illustrative and not in a limiting sense.

Having thus described my invention, I claim as new and desire to secure by Letters Patent:

1. In combination, a window frame, a window 25 slideable therein, a ventilator adapted to be placed in the window frame below said window, said ventilator comprising a case having a bottom wall, a front wall, a rear wall and end walls, said front and rear walls being formed with perforations, the rear part of said case extending above 30 the front part of said case and being substantially equal in width to the bottom of said window and located directly therebeneath, and the front part of said case projecting forwardly of said window, and a removable cover on said rear part of said case contacting said bottom of said window, and being formed with a baffle projection into said case and disposed parallel to said front and rear walls and projecting below the top of 40 the front part of the case.

2. A ventilator of the character described comprising a case having a bottom wall, a front wall, a rear wall, and end walls, said front wall being shorter than the rear wall, said front and rear 45 walls each being formed with a horizontal row of perforations, and a removable cover for the top of said case, frictionally engaging the case, said cover having an integral portion projecting into said case and disposed parallel to said front and rear walls, and serving as an air baffle, the rows of perforations in the front and rear walls being disposed above the lower edge of said baffle, the row of perforations in the rear wall being at a higher level than the row of perforations in 50 the front wall.

3. A window ventilator of the character described, comprising a case made of sheet metal and having a bottom wall, a front wall and a rear wall and end walls, said rear wall extending 55 to greater height than the front wall, a wall extending rearwardly from the top of the front wall, said front and rear walls being formed with perforations adjacent the upper ends thereof, and a cover for said case comprising a member having a channel to frictionally receive the upper edge 60 of the rear wall and having a wall engaging the rear end of the top wall and projecting below said top wall, thereby providing a baffle for air passing through the ventilator.

4. A window ventilator of the character described, comprising a member made of sheet metal and having a bottom wall, a front wall extending 65 from the front end of the bottom wall, a rear wall extending from the rear end of said bottom

wall, the upper edge of said rear wall being at a higher level than the top of said front wall, a top wall extending rearwardly from the top end of said front wall and terminating short of said rear wall, a downwardly extending flange on the 5 rear end of said top wall, said case being provided with end walls, said end walls interconnecting the top wall with the bottom wall and each having a horizontal edge somewhat below the top edge of the rear wall and a vertical edge extending above said top wall, and a cover for said case comprising a channel-shaped portion frictionally receiving the top edge of said rear wall, said cover having a top wall contacting said horizontal edges and a downwardly extending wall 15 contacting said vertical edges and projecting into the case and below said flange, said front and rear walls each being formed with a plurality of spaced perforations disposed above the lower edge of said downwardly extending wall. 20

5. A window ventilator of the character described, comprising a case having a bottom wall, a front wall, a rear wall and end walls, said rear wall extending to a greater height than the front wall, a wall extending rearwardly from the top 25 of the front wall and terminating short of said rear wall, said front and rear walls being formed with perforations adjacent the upper ends thereof, and a cover for said case having a wall engaging the rear end of said top wall and projecting below said top wall, thereby providing a baffle 30 for air passing through the ventilator.

6. A window ventilator of the character described, comprising a member having a bottom wall, a front wall extending upwardly from the front end of said bottom wall, a rear wall extending upwardly from the rear end of said bottom wall, the upper edge of said rear wall being at a higher level than the top of said front wall, a top wall extending rearwardly from the top end 40 of said front wall and terminating short of said rear wall, said case being provided with end walls interconnecting the top wall with the bottom wall and each having a horizontal edge somewhat below the top edge of said rear wall and a vertical 45 edge extending above said top wall, and a cover for said case having a top wall contacting said horizontal edges, and a downwardly extending wall projecting into the case and substantially contacting the rear end of said top wall of said case. 50

7. A window ventilator of the character described, comprising a member having a bottom wall, a front wall extending upwardly from the front end of said bottom wall, a rear wall extending upwardly from the rear end of said bottom wall, the upper edge of said rear wall being at a higher level than the top of said front wall, a top wall extending rearwardly from the top end of said front wall and terminating short of said rear wall, said case being provided with end walls interconnecting the top wall with the bottom wall and each having a horizontal edge somewhat below the top edge of said rear wall and a vertical edge extending above said top wall, and a cover for said case having a top wall contacting said horizontal edges, and a downwardly extending wall projecting into the case and substantially contacting the rear end of said top wall of said case, said front and rear walls each being 60 formed with a plurality of spaced perforations disposed above the lower edge of said downwardly 65 extending wall. 70
